UNITED STATES PATENT OFFICE.

BURR A. KENNEDY AND JOHN F. STEWARD, OF CHICAGO, ILLINOIS.

MACHINE FOR FOLDING AND STITCHING THE EDGES OF CANVAS.

SPECIFICATION forming part of Letters Patent No. 410,246, dated September 3, 1889.

Application filed June 26, 1888. Serial No. 278,181. (No model.)

To all whom it may concern:

Be it known that we, BURR A. KENNEDY and JOHN F. STEWARD, citizens of the United States, residing at Chicago, in the county of Cook and State of Illinois, have invented certain new and useful Improvements in Machines for Preparing Canvas for Use in the Manufacture of Conveying and Elevating Aprons for Harvesting-Machines, &c., of which the following is a full, clear, and exact specification, reference being had to the drawings forming a part hereof.

In the manufacture of conveying and elevating aprons or belts for harvesting machinery it is the practice to turn the edges of the fabric inward and stitch them down upon the body portion, or, in other words, to hem the edges, and thereafter to apply wooden slats across the face of the fabric.

The object of our invention is to provide a mechanism by which the two edges of the heavy fabric may be hemmed and flattened down simultaneously and rapidly preparatory to the presentation of the fabric to the machine which applies the slats.

Our invention embraces as essential elements a table or support for the fabric as it is drawn continuously from the roll, folding mechanisms to turn the two edges inward, a board or pressure device to maintain the extension of the fabric, pressure devices acting to flatten down the folded edges, and two sewing-machines to stitch the folded edges, as will hereinafter more fully appear.

In the accompanying drawings, Figure 1 is a side elevation of our mechanism and of the slatting-machine arranged adjacent thereto. Fig. 2 is a top plan view of our machine, the center portion being broken away in order to reduce the width of the figure. Fig. 3 is a perspective view showing in longitudinal vertical section the folding, extending, and pressing devices at one side of the machine. Fig. 4 is a longitudinal vertical section on the line $x-x$, Fig. 2. Fig. 5 is a cross-section through one side of the machine, showing a part of the folding mechanism.

Referring to the drawings, E^2 represents the roll of canvas or other fabric supported horizontally in standards E' . The end of the fabric is carried from the roll upward over a supporting or guiding roll E^3 , and carried

thence forward over the horizontal bed or table E , supported on a rigid frame D , which may be of any construction adapted to sustain the parts hereinafter described. Beyond the edge of the table, after passing over the table, the fabric passes between two horizontal power-driven rolls h h' , which serve the double purpose of flattening down the folded edges and of feeding the fabric forward, so as to relieve the feed mechanism of the sewing-machines hereinafter described. Before the fabric reaches the rolls it is acted upon at the two edges by folding mechanisms, 65 whereby the edges are folded or turned inward upon the body. There are now known in the art various folding mechanisms which may be employed for this purpose; but we recommend the particular devices shown in the drawings. These consist on each side of the machine of a plate f^2 and a second plate g . The plate f^2 is secured at its outer end to the bed or table, and has its inner end turned upward in the form of an inverted V , 70 as shown in Fig. 3, whereby it is adapted to turn the edge of the fabric upward and inward slightly past the perpendicular. The second plate g is fixed rigidly to the table at its outer end, but is slightly elevated at the inner end, so as to overlie the edge of the fabric and complete the folding down of the edge.

In order to keep the fabric extended and to maintain a uniform width thereof a plate or board F is laid horizontally across the table between the folding devices in position to rest on top of the fabric. This plate extends at the ends beneath the folding-plates g in order to prevent the latter from folding the edges 90 inward beyond the proper limit. The plate is held in position at each end by an arm f^4 , journaled at one end in a bearing-block f^6 upon the plate, and journaled at the opposite end in a supporting-block f^8 on the bed or table. These arms, of a round form in cross-section, extend obliquely across the edge of the fabric between the first and second folding-plates, and assist the same in turning the edges down over the end of the plate F . 100 After the fabric has passed the folding devices and the rolls its edges pass through two sewing-machines B B' , seated on opposite sides of the frame. These machines, which are not

- in themselves claimed as of our invention, may be of any ordinary or approved form. Various machines suitable for the purpose are now sold in the market. Each machine should comprise, as usual, feeding and stitching devices, and the machines should be one right-handed and the other left-handed, in order that they may act upon opposite edges of the fabric traveling between them. Driving mechanism of any suitable character may be employed for imparting motion to the rolls and the sewing-machines. We recommend, however, the arrangement represented in detail in Figs. 1 and 2, in which G is a horizontal driving-shaft mounted in the base of the machine, and provided at one end with a pulley G', connected by a belt G⁴ to a pulley G³ on one end of the roll h. The upper roll h is in this instance driven by the friction of the canvas passing between the two. A lever K, mounted on one side of the frame and provided at one end with an idler or tightener pulley acting on the belt G⁴, enables the operator to stop and start the rolls at will, while the driving-shaft continues in motion. The driving-shaft G is also provided with a second pulley G², from which a belt is extended to a pulley on the inner end of a horizontal shaft H, seated in bearings in the base of the frame. The shaft H is provided near each end with a pulley H', from which belt H² is extended upward to the driving-pulley of the corresponding sewing-machine. Each side of the frame may be provided with a tightener-lever L, acting on the adjacent belt H² for the purpose of stopping and starting the sewing-machine independently of the other parts.
- In order to adapt the machine for the production of aprons of different widths, the folding and sewing mechanisms may be made laterally adjustable. In the drawings we have shown an extra series of holes 1, 2, 3, 4, and 5 to receive the fastening-bolts of the folding devices at one side of the machine, so that these parts may be unbolted from the position in which they are shown and moved outward toward the edge of the table. When the folding devices are moved apart, the plate or board F may be replaced by another of greater length; or the board F may be made in two parts adjustable endwise in relation to each other to admit of its extension. One construction to this end is represented in dotted lines, which show the two parts with longitudinal arms or tongues d, fitted together and held by a transverse clamping-bolt d'. These details of construction are not of themselves claimed as part of the invention.
- The sewing-machines are arranged to slide inward and outward to and from each other, being guided at one side by means of lips b, seated in slots b' in guide-plates b². The clamp-screws b³ or equivalent fastening devices may be used to hold each machine in place.

The operation of the machine is as follows:

The canvas wound upon the supporting-roll, as shown at E², is carried over the roll E³, and thence over the table through the folding devices beneath the plate F and between the rolls h h' to the sewing-machines. As the fabric moves forward its edges are folded inward before reaching the rolls. The latter act to press the edges downward flatly and firmly upon the body of the fabric. The pressure devices for this purpose are an important feature of our machine, the weight and stiffness of the fabrics used for conveyer-aprons being such that it is necessary to subject the folded edges to severe pressure in order that they may not spring upward from the surface. The power-driven rolls serve, also, as a feed mechanism, drawing the fabric forward forcibly through the folding devices and delivering it to the sewing-machines, which are thus relieved from the excessive strain to which they would otherwise be subjected. Being located in advance of the sewing-machines, the rolls also insure the feeding of the two edges of the fabric at the same speed and the delivery of the fabric in flat form, so that the machines may be brought successfully thereon. After passing the sewing-machines the fabric escapes from the table.

We are aware that folding devices and sewing-machines have been arranged to act upon the two edges of a fabric simultaneously; but we believe ourselves to be the first to employ a feed mechanism in advance of the sewing-machines, the first to locate in advance of the sewing-machines a pressure-plate to flatten and maintain the width of the fabric, and the first to employ between the folding devices and the sewing-machines a pressure mechanism to flatten down the folded edges. In some cases the stitching of the folded edges is omitted. In such cases the sewing-machines of our structure may be removed or thrown out of action, in which case the remaining devices will act to fold and press down the two edges of the fabric.

In order to facilitate the manufacture, we commonly locate the slatting-machine C adjacent to our mechanism, as shown in Fig. 1, passing the end of the fabric over suitable guide-pulleys I I² to the second machine. The slatting-machine, as shown in the drawings, is not of our invention, being of the style known in the market as the "Kingwell machine."

Having thus described our invention, what we claim is—

1. The bed or table and the two folding mechanisms at opposite sides, in combination with the intermediate pressure-plate, the rolls beyond said plate, and the two sewing-machines beyond the rolls, whereby the machine is adapted to fold, press down, and finally stitch down the two edges of the fabric.

2. In combination with the table, the overlying plate F to act on top of the fabric, its sustaining-arms, the folding-plates f², and

the folding-plate *g*, overreaching the end of plate *F*, as shown.

3. In a machine for folding and stitching the opposite edges of a fabric simultaneously, the combination of a supporting bed or table, a folding mechanism and a sewing mechanism at each side of the table, and a feed mechanism located between the folding and the sewing mechanisms and extending across

the path of the fabric from side to side, whereby the fabric is advanced equally at the two sides and the feed devices of the sewing-machines relieved from labor.
